UNITED STATES PATENT OFFICE.

RALPH D. MERSHON, OF NEW YORK, N. Y., ASSIGNOR TO THE WESTINGHOUSE ELECTRIC & MANUFACTURING COMPANY, A CORPORATION OF PENNSYLVANIA.

LIGHTNING-ARRESTER.

No. 893,742.

Specification of Letters Patent.

Patented July 21, 1908.

Application filed September 27, 1904, Serial No. 226,103. Renewed July 16, 1906. Serial No. 326,498.

To all whom it may concern:

Be it known that I, RALPH D. MERSHON, a citizen of the United States, residing at New York, in the county and State of New York, 5 have invented certain new and useful Improvements in Lightning-Arresters, of which the following is a specification, reference being had to the drawing accompanying and forming part of the same.

One of the most serious problems met with in electric power transmission is the protection of the lines and apparatus connected therewith from the destructive effects of lightning and other static disturbances, such 10 as might follow the interruption of a circuit, etc., and the prevention of after disturbances of the system. A large variety of "lightning arresters" have been proposed and have been found more or less successful in practice. 15 My invention, however, possesses certain advantages which have not been found in the prior devices with which I am familiar. Those now in use, especially those for use on high voltage circuits, will take light dis- 20 charges and successfully interrupt the dynamo current which follows, but they are inadequate for dealing with heavy discharges. One of the principal reasons for this ineffectiveness is that in order for them to success- 25 fully interrupt the generator current there is usually included in series with the arrester a resistance to limit the current which follows the discharge. This resistance, in order to be effective for limiting the generator cur- 30 rent, is given so high a value that a very heavy discharge cannot readily pass through it, resulting in a piling up of potential at the time of such heavy discharge. If the resist- 35 ance be given a lower value, to permit heavy discharges to pass, resulting in a conse- 40 quently greater disturbance on account of the dynamo current which follows, then this greater disturbance will occur with all dis- 45 charges, both light and heavy.

It is the object of my invention to provide 50 protecting devices which shall not only take care of the lightning discharge, thus saving the costly apparatus of the system from injury, but also such as will cause the disturbances to the system, due to the dynamo current which follows the discharge, to be proportional, or approximately so, to the necessities of the case. That is, where the lightning or other static discharge is small, 55 the after effects upon the system will be

slight, while considerable disturbances will be caused only by heavy discharges from which the apparatus must be protected at any cost of after disturbance.

In carrying out my invention I provide a 60 plurality of arresters connected to the ground independently or through portions of common resistance, of such character, and so proportioned as to their resistance as to provide paths suited for lightning discharges or 65 other static disturbances of various magnitudes and to permit the following of dynamo current only in more or less direct proportion to the magnitude of the discharge.

The invention will be more readily understood by referring to the accompanying drawings, in which

Figure 1 is a diagram showing the preferred form. Fig. 2 is a modification, and Figs. 3, 4, and 5 show other convenient em- 75 bodiments.

In Fig. 1 are shown two series of four arresters, *a*, *b*, *c*, *d*, of the well known "horn" type, each series connected to one of the line conductors *l*, *l'*. The first of these devices 80 indicated by *a*, is adapted to take care of a light discharge, and the arcing gap between the horns is therefore narrow. The device is connected to the ground *G* through a com- 85 paratively large resistance *r*. In the re- 90 maining devices, which may be one, two, three or more, in number, the horns are spaced farther apart successively, and are connected with successively lower resist- 95 ances, as shown, the last being preferably connected directly to the ground. The first pair of horns are so spaced that the dielectric between them will be broken down by a com- 100 paratively small static disturbance. The arc resulting from the dynamo current fol- 105 lowing the discharge will tend to be put out by rising between the divergent horns and by the high resistance in series with them, and the path to the ground thereby broken.

However, if the arc persists, the resistance *r* and the rising of the arc on the horns will effectively limit the amount of the relatively low tension dynamo current which can follow, giving the arc time enough to rise upon the horns until it is extinguished. The disturbance due to flow of dynamo current is therefore slight, and not infrequently is in- 110 appreciable. If the discharge is more violent, to take care of it properly so as to prevent damage to the apparatus on the line

makes it necessary to employ a lower resistance to the ground. The greater difference of potential due to the more violent discharge will also result in an arc between the horns 5 *b*, separated proportionally to the striking electromotive force which it is desired they shall take care of, and which are connected to the ground through a lower resistance than is used with the device *a*. Both devices, *a* and *b* are therefore in operation simultaneously. In this case, if the arc or 10 arcs persist, the lower resistance connected with the horns will of course permit a larger flow of dynamo current, but the apparatus 15 on the line will be protected from injury. With a still more violent bolt the device *c* will come into operation, and for an instant all three will be discharging. The horns of the device *c* are still farther separated and 20 the resistance to ground still lower. The combined action of the three devices protects the apparatus (this time from a discharge which might otherwise wreck it) though at a cost of greater disturbance to 25 the system if the arc or arcs do not go out immediately. Finally the fourth pair of horns, *d*, farther separated than any of the others, are connected directly to the ground, or through very low resistance. These horns 30 are so spaced that the dielectric between them will be broken down only when the maximum voltage, which the system can withstand without injury, is exceeded, as by a lightning or other discharge. In the 35 circuit of the horns *d* is also included an automatic circuit breaker, as a fuse *f*, or any other convenient device. This last arrester protects the system from extremely powerful discharges, but of course the absence or 40 comparative absence of resistance would allow proportionally greater flow of dynamo current. The effect might even be practically or quite equal to a short circuit. Before the latter could cause any damage, however, 45 it is intended that the circuit to ground through the last pair of horns should be broken by the fuse *f*, or other device by the heavy dynamo current following the lightning discharge. The last arrester therefore 50 operates as a sort of safety valve to take care of extraordinary conditions which might otherwise cause damage to the apparatus which would entail much more serious loss and annoyance than would the comparatively 55 brief disturbance of the system due to the heavy flow of dynamo current and subsequent operation of the fuse or other device *f*. As stated before, any number of arresters 60 may be used. Extraordinary precautions 65 may require a considerably larger number than I have shown. Also, each or any of the arresters may be provided with a circuit breaker, as a fuse or other device, if desired, so as to open the ground circuit if the arc is very persistent and the current flow from the

dynamo considerable. It will be understood, of course, that the line wires, whether two, three or more in number, are each protected by a system of arresters. It is evident that the resistances employed in series with the discharge gaps need not necessarily be in any manner proportional to the width of the spark gaps themselves but may have any other value. For instance, the resistances may be equal. In this case the various discharge 70 gaps would still have the consecutive and cumulative action which characterizes the invention, although the protective effect would not increase so rapidly with the successive breakdown of the gaps as with resistances proportioned as described above. 80

The system of protecting devices shown in Fig. 2 has automatic circuit breaking devices, as shown, in all the ground circuits, in lieu of resistances. It has, however, the same advantages of cumulative and consecutive operation as the arrangement just described, and in addition the advantage that all the paths to earth are of very low resistance, though it possesses one feature 90 which under certain circumstances may be a drawback, in that for the lighter discharges disturbance to the system will be greater than if the consequent dynamo current were limited by resistance. Each one of the discharge paths shown in this figure is supposed to have as low an ohmic resistance as possible. The ohmic resistance of the discharge path to ground may be reduced by increasing the total effective cross section of the path; but 100 the inductive resistance of the path cannot be materially reduced by increasing its cross section. If it is desired to diminish the inductive resistance the path must be subdivided, or duplicated, in multiple, as is done 105 in the figure referred to. It is evident that this reduction of the inductive resistance accompanies also, to a greater or less extent, the other devices which are described herein, especially where each discharge gap has its 110 own separate path to the ground, as in the case of Fig. 3. It will of course be understood that both line wires or "legs" of the circuit in Figs. 2 and 3 are to be provided with protecting devices, as in Fig. 1. 115

From the foregoing explanation it will be noted that the essence of my invention resides in the use of a plurality of devices of successively higher striking potentials connected to ground, so constructed and arranged, as herein described, that the resultant disturbance to the system is proportional only to the necessity of the case. Where resistances are used they may be of values successively lower, corresponding to the successively higher striking electromotive forces of the devices. 120

In Fig. 4 the similar arresters *a'*—*a'*, *b'*—*b'*, *c'*—*c'* for the different line conductors are connected to common grounds *G'*, *G''*, *G'''*, 125

and have independent resistance r' , r'' , the devices being provided with fuses f' , f'' , or other automatic circuit breakers.

In Fig. 5, the ordinary saw-toothed devices a'' , b'' , are used instead of horns, connected to the line conductors l , l' , and ground G^4 , G^5 , as in Fig. 2. Fig. 5 also shows choking coils h , h , which may of course be used with the other arrangements if desired. The last device has fuses or other circuit breakers f'' , as in the embodiments previously described.

I am aware that it has been proposed heretofore to employ two or more arresters of different striking potentials, and I therefore do not claim that idea broadly as my invention. So far as I am aware, however, the prior devices of that character have all employed reactance or resistance between the various paths to ground. I prefer to use no artificial reactance and resistance between the various discharge paths, since I have discovered that it is in general desirable that the reactance and resistance be minimum—that is, that the self-induction and resistance between the discharge paths be only such unavoidable amount as, for example in the arrangement shown in Fig. 1, the line conductor may produce of itself. This may be made so small as to be practically negligible, so that it may be said that there is substantially no inductance or resistance between the paths. This feature is expressed in the appended claims by the statement that the connections from path to path on the system side are of low reactance and resistance, in contradistinction to connections which include artificial reactance or resistance. The object of keeping the reactance and resistance as low as possible is to make the conditions such that all the paths will be subjected to substantially the same potential. The gap of lowest striking potential will then break down first, followed by as many more of higher striking potentials as may be necessary to take care of the discharge.

The invention is of course applicable not only to transmission systems, but also to any other electrical system which it is desired to protect from static disturbances, and to any part of the same, and may be embodied in a variety of forms without departing from its proper scope.

What I claim is:

1. The combination with an electric line conductor, of a series of grounded discharge paths spaced apart and connected to said line conductor in multiple and severally provided with discharge gaps of successively higher striking potentials, the connections on the line side of the gaps being of low reactance and resistance, in contradistinction to connections which include artificial reactance and resistance, as set forth.

2. The combination with an electric line

conductor, of a series of grounded discharge paths spaced apart and connected to said line conductor in multiple and severally provided with discharge gaps of successively higher striking potentials, the connections on the line side of the gaps being of low reactance and resistance, in contradistinction to connections which include artificial reactance or resistance, and artificial resistance in one or more of the paths, as set forth. 75

3. The combination with an electric line conductor, of a series of grounded discharge paths spaced apart and connected to said line conductor in multiple and severally provided with discharge gaps of successively higher striking potentials and with successively lower resistances between the gaps and the ground, as set forth. 80

4. The combination with an electric line conductor, of a series of grounded discharge paths spaced apart and connected to said line conductor in multiple and severally provided with discharge gaps of successively higher striking potentials and with successively less amounts of a common artificial resistance 90 in all but one of said paths, as set forth.

5. The combination with an electric line conductor, of a series of grounded discharge paths spaced apart and connected to said line conductor in multiple and severally provided with discharge gaps of successively higher striking potentials, the connections to the line conductor being of low reactance and resistance, in contradistinction to connections which include artificial reactance or resistance, and automatic circuit-breaking means 100 in one or more of the paths, as set forth.

6. The combination with an electric line conductor, of a series of grounded discharge paths spaced apart and connected to said line conductor in multiple and severally provided with discharge gaps of successively higher striking potentials and with successively lower resistances between the gaps and the ground, and automatic circuit-breaking 110 means in one or more of the paths, as set forth.

7. The combination with an electric line conductor, of a series of grounded discharge paths spaced apart and connected to said line conductor in multiple and severally provided with discharge gaps of successively higher striking potentials and with successively less amounts of a common artificial resistance 120 in all but one of the paths, and automatic circuit-breaking means in one or more of the paths, as set forth.

8. The combination with an electric line conductor, of a series of grounded discharge paths spaced apart and connected to said line conductor in multiple and severally provided with discharge gaps of successively higher striking potentials and with successively lower amounts of resistance between the gaps and the ground, and automatic cir- 130

- cuit-breaking means in the path having the discharge gap of highest striking potential, as set forth.
9. The combination with an electric line conductor, of a series of grounded discharge paths spaced apart and connected to said line conductor in multiple and severally provided with discharge gaps of successively higher striking potentials and with successively less amounts of a common artificial resistance in all but one of the paths, and automatic circuit-breaking means in the path having the discharge gap of highest striking potential, as set forth.
10. In a protective system for electrical circuits, a series of discharge gaps spaced apart and interposed between the line to be protected and the ground, and non-inductive resistances of different values between successive adjacent gaps.
11. In a protective system for electrical circuits, a series of discharge gaps spaced apart and interposed between the line to be protected and the ground and non-inductive resistance paths of different values between the respective gaps and the ground.
12. In a protective system for electrical circuits, a series of discharge gaps of different striking potentials spaced apart and interposed between the line to be protected and the ground, and non-inductive resistances of different values interposed between the gaps and the ground.
13. In a protective system for electrical circuits, a series of discharge gaps of different striking potentials spaced apart and interposed between the line to be protected and the ground, and resistances interposed between the gaps and the ground, the values of which are inversely proportional to the striking potentials of the gaps to which they are connected.
14. In a protective system for electrical circuits, a series of paths spaced apart and interposed between the line to be protected and the ground and respectively comprising discharge gaps and resistances of different values upon one side only of the gaps.
15. In a protective system for electrical circuits, a series of paths spaced apart and interposed between the line to be protected and the ground and respectively comprising discharge gaps and resistances of different values between successive adjacent gaps upon one side only thereof.
16. In a protective system for electrical circuits, a series of paths spaced apart and interposed between substantially equi-potential points of the line to be protected and the ground and respectively comprising discharge gaps of different striking potentials and resistances upon one side only of the gaps.
17. In a protective system for electrical circuits, a series of discharge gaps spaced apart and interposed between the line to be protected and the ground, and resistances of different values between the grounded terminals only of successive adjacent gaps.
18. In a protective system for electrical circuits, a series of discharge gaps spaced apart and interposed between the line to be protected and the ground, and resistance paths of different values between the grounded terminals only of the respective gaps and the ground.

RALPH D. MERSHON.
